CLAIM

We claim the ornamental design for a multi-lavatory system, as shown and described.

DESCRIPTION

FIG. 1 is a perspective view of a preferred embodiment of a multi-lavatory system.

FIG. 2 is a front elevation view of the multi-lavatory system.

FIG. 3 is a top plan view of the multi-lavatory system.

FIG. 4 is a left-side elevation view of the multi-lavatory system wherein the right-side elevational view is a mirror image of the left.

FIG. 5 is a perspective view of a second embodiment of a multi-lavatory system.

FIG. 6 is a front elevation view of the second embodiment of the multi-lavatory system.

FIG. 7 is a top plan view of the second embodiment of the multi-lavatory system; and,

FIG. 8 is a left-side elevation view of the second embodiment of the multi-lavatory system wherein the right-side elevation view is a mirror image of the left-side elevation view.
